UNITED STATES PATENT OFFICE.

CARL MICHEL, OF GRENCHEN, ASSIGNOR TO EMIL ZETTER, OF SOLOTHURN,
SWITZERLAND.

ADDRESS-HOLDER FOR UMBRELLAS, STICKS, &c.

SPECIFICATION forming part of Letters Patent No. 415,116, dated November 12, 1889.

Application filed June 20, 1889. Serial No. 315,029. (No model.) Patented in Switzerland February 6, 1889, No. 538.

To all whom it may concern:

Be it known that I, CARL MICHEL, a citizen of the Republic of Switzerland, residing at Grenchen, in the Republic of Switzerland, have 5 invented a certain new and useful Address-Holder for Umbrellas, Sticks, Traveling-Bags, and other Traveling Objects (for which I have obtained a patent in Switzerland, No. 538, dated February 6, 1889,) of which the following is a specification.

My invention relates to devices adapted to be attached either permanently or temporarily to umbrellas, canes, traveling-satchels, and other similar articles used by travelers, 15 and has for its object to enable the finder of such articles which are accidentally left or forgotten by the owner in railway-cars, hotels, &c., to promptly return the same without trouble or outlay.

With this object in view my invention consists of the peculiar construction and combination of parts of the address-holder, which will be hereinafter more fully described and claimed, which is adapted to form an attachment 25 to the articles in connection with which it is intended to be used.

Reference being had to the accompanying drawings, which form a part of this specification, Figure 1 represents a longitudinal sectional view of my improved address-holder. Fig. 2 is a cross-section of the same on line xx . Fig. 3 is a side view of an umbrella-handle or cane-handle provided with this attachment. Fig. 4 is a similar view showing 35 the manner of using the device; and Fig. 5 is a view of an umbrella or cane handle, illustrating a slightly-modified form of the attachment and the manner of applying it to the article.

Like letters of reference denote corresponding parts in all the figures.

The letter e denotes the handle of an umbrella or a cane provided with my address-holding attachment, which is shown at a . 45 This attachment consists simply of a cylindrical box made of metal or other suitable material, of convenient size, and terminating at its lower end in a solid bottom b' , which has a screw-threaded central aperture, (shown 50 at g .) The top of this box is closed by a plug

b^2 , the under side of which is preferably beveled, as shown in Fig. 1, so as to fit watertight against the beveled top rim of the cylinder a . Fastened in and projecting downwardly from the center of the plug b^2 is a 55 stem or spindle b , the lower end of which is enlarged to form a disk b^3 , below which said stem or spindle terminates in a screw b' , adapted to be screwed into the threaded aperture g in the lower end of the box. The 60 latter may be attached to the handle of the umbrella in many various ways, and, among others, it may be fastened thereto by means of a metallic strap or band d , as shown in Figs. 3 and 4; or, if desired, the body of the 65 handle may be provided with a cylindrical recess or bore, as shown at f in Fig. 5, adapted to fit the box a , which in that case may be screw-threaded on the outside, so that it may be screwed into the recess and held firmly in 70 place therein. Where that construction is adopted, the plug or cover b^2 may be provided with a notch for its removal with the aid of a screw-driver or other implement.

Around the stem or spindle b is wound a 75 ticket or label c , made of parchment paper, leather, soft metal, or any other suitable flexible material possessing sufficient strength, and this label has inscribed upon it the name and address of the owner of the article to 80 which the device is attached. It may also be provided with one or more postage-stamps, insuring the prepayment of the article if the same is to be transmitted to its owner through the mails. Under normal conditions this label 85 is contained within the cylindrical box or holder a , where it is entirely out of the way of injury by rain or dampness. The cylindrical box or the knob or cover thereof should be provided with a suitable inscription requesting the finder of the article to unscrew 90 the top and affix the label in the manner illustrated in Fig. 4, and then deposit the article in the nearest post-office.

To facilitate the attachment of the address-label, the same may be provided at one end with a hole sufficiently large for the insertion of the stem or spindle b , which is then again fastened in the box by screwing its lower threaded end into the threaded aperture g in 100

the bottom of the box. In this manner the label will be held firmly in place, as shown in Fig. 4, in a conspicuous position, and after the article in question has been deposited at 5 the post-office it will be returned without any expense or outlay on the part of the finder to its proper owner, according to the address given on the label.

The object of the enlargement or disk b^3 at 10 the lower end of the spindle b is to insure the withdrawal of the address-label from the box upon the removal of the knob b^2 , as, in the absence of this enlargement at the lower end of the spindle, the latter would slip 15 through the label without carrying it with it.

Having thus described my invention, I claim and desire to secure by Letters Patent of the United States—

1. The detachable address-label holder 20 herein described, consisting of the cylindrical box a , having a threaded aperture in its lower end, in combination with the knob or cover b^2

and central stem or spindle b , provided with the disk or enlargement b^3 and screw-threaded projection b' , substantially as and for the 25 purpose set forth.

2. The combination, with an umbrella or similar portable article, of the herein-described address-label and holder for the same, the same comprising the cylindrical box a , 30 the knob b^2 , having spindle b , provided at its lower end with the enlargement b^3 and screw-threaded projection b' , flexible address-label c , and means, substantially as described, for attaching the box, with its contents, upon the 35 article to which it is to be affixed, substantially as and for the purpose set forth.

In testimony whereof I have hereunto signed my name, in the presence of two subscribing witnesses, this 5th day of April, 1889. 40

CARL MICHEL.
